ANIMAL FIGURE DOLL

Anthony Chrones, 52 Wood Haven Blvd.,
North Providence, R.I. 02908

Filed May 25, 1970, Ser. No. 23,129

Term of patent 14 years

Int. Cl. D21—02

U.S. Cl. D34—2

FIG. 1

FIG. 2

FIG. 3

FIG. 4

FIG. 5

FIG. 1 is a plan view of one side of an animal figure doll embodying my new design, the opposite side being identical;

FIG. 2 is a top plan view thereof;

FIG. 3 is an edge view thereof;

FIG. 4 is an edge view from the edge opposite FIG. 3;

FIG. 5 is a bottom plan view thereof.

I claim:

The ornamental design for an animal figure doll, as shown and described.
